UNITED STATES PATENT OFFICE.

JAY COOK, OF COLDWATER, MICHIGAN.

CLINKER-BURNER.

1,308,936.

Specification of Letters Patent. Patented July 8, 1919.

Application filed February 26, 1919. Serial No. 279,462.

To all whom it may concern:

Be it known that I, JAY COOK, a citizen of the United States, residing at Coldwater, in the county of Branch and State of Michigan, have invented a new and useful Clinker-Burner, of which the following is a specification.

The device forming the subject matter of this application is a burner, adapted to be placed on the grate of a stove, furnace, boiler fire box or other structure of a like sort for the purpose of affording heat, and especially for the purpose of diffusing gas through clinkers or like material.

The invention aims to improve the construction of the burner, generally considered, to improve the coöperation between the burner and the flame spreader, to provide means whereby the flame spreader may be adjusted toward and away from the base of the burner, and to provide novel means for feeding liquid fuel to the burner.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows an elevation, a burner constructed in accordance with the invention, mounted on the grate, and assembled with the oil feeding means, parts appearing in section; Fig. 2 is a section taken through the burner proper, a portion of the grate appearing; and Fig. 3 is a transverse section looking downwardly upon the base of the burner.

In carrying out the present invention, there is provided a burner, denoted generally by the numeral 4 and comprising a hollow base 5 having a top 3 which is downwardly concaved as shown at 2. The base preferably includes a flat bottom 50, whereby the base is supported immediately upon the grate 1 of a stove, furnace, boiler fire box or other structure. The top 3 of the base 5 is supplied, preferably, with a single perforation 7 located at the lowermost portion

of the concavity 2 of the top. The top 3 is supplied with depending bosses 51 into which upstanding supports 8 are threaded, the supports preferably being in the form 60 of rods.

The numeral 9 denotes a flame spreader and it may have a flat top 54, the lower surface of the flame spreader being convexed, as shown at 52, to conform to the concavity 2 65 of the top 3 of the base 5. The supports 8 pass slidably through the flame spreader 9 and the flame spreader is held on the supports 8, for vertical adjustment, toward and away from the base 5, by means of nuts 10 70 on the supports, the upper nuts 10 coacting with the flat upper surface 54 of the flame spreader, and the lower nuts 10 coacting with the recesses 53 formed in the lower surface of the flame spreader. 75

A pipe 11 is connected as shown at 6 with the base 5 and opens thereinto, the pipe leading to the tapered lower end 55 of a tank 13 having a tapered top 57. A valve 12 is interposed in the pipe 11. A piston, denoted 80 generally by the numeral 56, operates in the tank, and includes a head 14 slidably mounted in the body portion of the tank, the head being carried by a stem 15 slidable in the top 57. A platform 16 is mounted on the 85 upper end of the stem 15 and is adapted to receive a weight.

In practical operation, the burner, supported on the grate 1, is surrounded by clinkers or other incombustible material. If, 90 however, the clinkers are still combustible to any extent, the combustible material will be burned away, thereby effecting a saving of fuel, and leaving the burner surrounded by a mass of non-inflammable material. 95 When a weight is placed on the platform 16, the stem 15 and the piston head 14 are forced downwardly, thereby effecting a feeding of the oil through the pipe 11, the flow of oil being regulated by the valve 12. The oil 100 passes into the hollow base 5 and is converted into gas. The gas issues through the opening 7 and is deflected by the member 9 into the surrounding clinkers or other incombustible material, the gas, of course, being ignited. The result is that there is upon the grate 1, a bed of hot coals resulting from the burning of the gas in the incombustible clinkers or like material. 105

Any desired means may be employed for 110 forcing the oil from the tank 13 to the burner.

Having thus described the invention, what is claimed is:

In a device of the class described, a hollow base having an imperforate bottom and a top concaved downwardly from its periphery to its center, the top being provided with a perforation; means for admitting liquid fuel to the base; upstanding supports carried by the top of the base; a spreader 10 adjustable on the supports toward and away from the base and having its lower surface convexed downwardly from its periphery to its center into approximate parallelism with the top of the base; and adjusting devices

on the supports, the adjusting devices coöperating with the upper and lower surfaces of the spreader and being movable longitudinally of the supports to adjust the position of the spreader with respect to the top of the base. 20

In testimony that I claim the foregoing as my own, I have hereto affixed my signature in the presence of two witnesses.

JAY COOK.

Witnesses:
